UNITED STATES PATENT OFFICE.

HERMAN BESSER AND JESSE H. BESSER, OF ALPENA, MICHIGAN.

DOOR FOR MIXING MACHINES.

Application filed May 23, 1921. Serial No. 471,795.

To all whom it may concern:

Be it known that we, HERMAN BESSER and JESSE H. BESSER, citizens of the United States, residing at Alpena, in the county of Alpena and State of Michigan, have invented certain new and useful Improvements in Doors for Mixing Machines; and we do hereby declare the following to be a full, clear, and exact description of the invention, such as will enable others skilled in the art to which it appertains to make and use the same.

This invention relates to mixing machines and pertains more particularly to machines for the mixing of concrete and similar materials.

One object of our invention is to provide in a machine of this class an improved means of discharging the material immediately upon the completion of the mixing operation and without stopping the paddles, the ejection of the material being accomplished by the mixing paddles.

With these and certain other objects in view which will appear later in the specification, our invention comprises the devices described and claimed and the equivalents thereof.

Fig. 1 is a transverse sectional view.
30 Fig. 2 is a fragmentary front view, showing the discharging door closed.

Fig. 3 is a similar view, showing the door open.

We provide a part-cylindrical stationary drum 1, which may be open at the top, as shown, or provided with a suitable cover, the rear or charging side of the drum formed with an apron 2 and the front or discharging side provided with a tight-fitting removable door or closure 3, the operation of which will be described presently.

A central revolvable shaft 4 is located axially in the drum, the shaft being mounted in suitable bearings carried by end plates 45 6 to which the drum 1 is secured.

Radial arms 7 secured to shaft 4 near its middle carry part-helical mixing blades 8 and 9, the outer edges of which travel in close proximity to the inner surface of drum 1, the ends of the blades traveling close to the inner faces of the end plates 6.

Blades 8 and 9 are so disposed with relation to each other that they both tend to move the material toward the middle of the length of the drum, thus eliminating end thrust on the shaft 4 and automatically

gathering the material toward the door 3. The opening 10 in the discharge side of the machine is provided with door 3, which fits the opening 10 when closed and has its inner face flush with the inner surface of the drum 1, the door having the same curvature as the drum. A flange 11 is provided around the outer edge of the door 3, to overlap the edges of opening 10.

A bar 12, having laterally projecting ends, is secured to the door 3, the ends of the bar being pivotally secured to the outer ends of a pair of arms 13 carried by a rock shaft 14 mounted on suitable bearings 70 on the end plates 6.

The rock shaft is provided with an operating handle 15.

A second bar 16, also having laterally projecting ends, is fixed to the lower edge 75 of door 3, the projecting ends of bar 16 slidably received on guides 17 carried by the drum 1 and spaced apart therefrom, as shown in Fig. 1.

When handle 15 is raised, rocking the arms 13, the door 3 is lifted bodily outwardly and upwardly from the position shown in Fig. 2 to that of Fig. 3, the lower part of the door being guided by the members 17 into the position shown in Fig. 1. 80 85

When handle 15 is swung downwardly, the door is closed, the guides 17 returning the lower part of the door 3 into proper relation with the opening 10, the lower parts of the guide 17 being closer to the drum 90 than their upper parts and serving to wedge the lower end of the door into place.

In operation, the charging is done from the top, and if concrete is being mixed, the cement, sand and gravel are first put in and mixed dry, then water is added and the mass is worked by the mixing blades 8 and 9 over and over and gradually collected from the ends of the drum toward the middle. Since the helical mixing blades 95 travel close to the ends of the drum and to its inner cylindrical surface, these surfaces are scraped quite clean and when the door 3 is open as above described, the material is lifted up and discharged from the opening 10 at each revolution of the blades until practically all of the material has been removed from the drum. It is then ready for 100 105

another charge.

By the means above described, we have 110 produced a simple and comparatively inexpensive, yet effective mixer that has few

working parts, is practically self-cleaning and self-dumping and does not necessitate the moving of heavy weights to discharge the material, as is the case with mixing machines that dump by inverting the mixing drum.

Having thus described our invention, what we claim and desire to secure by Letters Patent is:

10. 1. In a mixing machine, the combination of a stationary cylindrical drum, a discharge opening at one side of said drum, a removable door for said opening, guides engaging the lower part of said door; pivoted rocker arms connected to the upper end of said door, and a rock-shaft supporting said arms.

2. In a mixing machine, the combination of a stationary cylindrical drum, said drum formed with a side discharge opening, a removable closure for said opening, lateral projections near the lower edge of said closure, fixed guides engaging said projections, a rock-shaft, and a pair of rocker arms on said shaft, said arms pivoted to said closure near the upper part thereof.

In testimony whereof, we affix our signatures in presence of two witnesses.

HERMAN BESSER.
JESSE H. BESSER.
